CLAIM

The ornamental design for a display device, as shown and described.

DESCRIPTION

FIG. 1 is a perspective view a display device showing my new design;

FIG. 2 is a front elevation view thereof, the rear elevation view being a mirror image thereof;

FIG. 3 is a top plan view thereof;

FIG. 4 is a left side elevation view thereof, the right side elevation being a mirror image thereof;

FIG. 5 is a bottom view thereof;

FIG. 6 is a top plan view thereof, in section taken at 6—6 in FIG. 2 ; and,

FIG. 7 is a bottom view thereof, in section taken at 7—7 in FIG. 2.

The phantom lines in FIG. 1 depict a displayed item, and form no part of the claimed design.
